CLAIM

The ornamental design for a jewel setting, as shown and described.

DESCRIPTION

FIG. 1 is right front top perspective view of a jewel setting showing my new design.

FIG. 2 is a left front top perspective view thereof.

FIG. 3 is a top right rear perspective view thereof.

FIG. 4 is a front elevation view thereof.

FIG. 5 is a rear elevation view thereof.

FIG. 6 is a right side elevation view thereof.

FIG. 7 is a left side elevation view thereof.

FIG. 8 is top plan view thereof; and,

FIG. 9 is a bottom plan view thereof.

The dash-dash lines represent portions of the jewel setting that form no part of the claimed design. The dash-dot lines represent the bounds of the claimed design and form no part thereof.
